STOKER

Howard P. Anderson, Erie, Pa., assignor to The Standard Stoker Company, Incorporated, a corporation of Delaware

Application November 4, 1933, Serial No. 696,622

6 Claims. (Cl. 110—101)

This invention relates to mechanical stokers for boilers of locomotives and the like. It appertains particularly to that type of stoker in which the coal is conveyed to the base of, and is then pushed upwardly in columnar formation in, a comparatively long upstanding inclined conduit having a laterally opening mouth portion with a distributor head positioned therein or adjacent the mouth portion forward of the fuel column. The mouth portion permits the advancing column of coal to rise to a sufficient height above the distributor head so that the action of gravity will break the columnar formation of the coal and place the lower and forward edge of the sloping fuel face forward of the distributor head, whereby the jets issuing from the head will act upon the fuel, thus assisting the action of gravity in breaking its columnar formation, creating a more or less fixed angle of repose of the fuel dependent upon the kind and condition of the fuel being used, which jets project the coal over a distributor plate and scatter it over the firebox.

Ordinarily, in stokers of this type, the coal moves continuously through the conduit to the fuel projecting jets at a rate equal to the rate of combustion. This is desirable to procure the maximum efficiency and eliminate the smoke nuisance. There are times, however, when fine or slack coal of a low carbon content is used and when such coal is quite moist or very wet that it forms a compact sticky fuel column which rises above the distributor head and above the usual angle of repose before the action of gravity breaks the column. The result is that the coal breaks or drops intermittently onto the distributor plate in front of the distributor head in large gobs. This intermittent feed of heavy gobs of coal is objectionable because uniform distribution of the heavy gobs over the fire is difficult to obtain and control and the intermittent feed causes smoke and incomplete combustion.

The object of this invention is to obviate this objectionable intermittent feed of heavy gobs of coal by the provision in the upstanding conduit of means for splitting or breaking up the column of coal in advance of the action on the mass of coal by the pressure fluid jets.

Another object of the invention resides in the particular construction of that part of the conduit at or adjacent the fuel splitting means.

On the drawing—

Figure 1 is a fragmentary central vertical longitudinal sectional view showing the rear por-

tion of a locomotive firebox with the invention applied thereto;

Figure 2 is a fragmentary end view of the invention taken on the line 2—2 of Figure 1;

Figure 3 is a fragmentary plan view of the upstanding conduit of the invention with some portions broken away;

Figure 4 is a side elevational view of the upper end portion of the stoker conduit of the invention; and

Figure 5 is a view similar to Figure 1, illustrating a modification of the invention.

On the drawing the invention is illustrated, and it will be described, as applied to a locomotive firebox but it is capable of use with other furnaces or fireboxes of similar construction.

Referring to Figure 1, the firebox is represented at 10, its backhead at 11 and the firing opening therein at 12. Coal is conveyed from the locomotive tender (not shown) or other source of supply by the screw conveyor 13 within the housing 14 to the base of the upstanding inclined riser or discharge conduit 15 mounted in any suitable manner on the backhead 11 in communication with the firing opening 12. Forward of the spherical joint structure 16 the conduit 15 is substantially rectangular in transverse cross sectional shape.

After the coal leaves the end of the screw 13 it is forced upwardly in the conduit 15 the shape of which forms the coal into a column of substantially rectangular shape in cross section. As the column of coal advances it moves upwardly into the forwardly opening mouth portion 17 of the conduit where there is disposed in the lower portion thereof the distributor head or nozzle 18 positioned forward of the fuel column and the distributor plate 19 extending forward from the head into the firing opening. Jet openings as at 20 in the front face of the head above the plate communicate with pressure fluid chambers 21 supplied with pressure fluid such as steam by the pipes 22 for discharging fuel projecting blasts across the distributor plate.

The rear wall of the conduit 15 including its separate hood or cover portion 23 extends upward above the distributor head and plate in a substantially continuous line with its lower portion, a distance sufficient to permit the angularly advancing column of coal under ordinary conditions to rise to a height above the distributing plate so that the action of gravity may break the columnar formation of the coal and place the lower and forward edge of the sloping fuel face forward of the distributor head. The jets dis-

charging from the openings 20 then act to project the coal forwardly across the distributor plate into the firebox and thus assist the action of gravity under ordinary conditions to maintain a more or less fixed angle of repose of the fuel in the mouth portion of the conduit.

As heretofore explained there are times representative of unusual conditions when the column of coal rises above the distributor head and intermittently breaks over the ledge formed by the head in heavy gobs instead of breaking away continuously as the coal rises. Thus far the construction and operation described is well known.

The present invention resides chiefly in the provision of fuel splitting means in the conduit 15 now to be explained. This means consists preferably of a plurality of spaced wedges 24 disposed in alignment transversely of the conduit 15 on the rear wall thereof and being equally spaced from one side wall to the other. Each wedge is constructed in approximately the form of a tetrahedron and disposed on the rear wall in the path of the advancing column of coal and arranged with two triangular sides thereof extending angularly toward one another from the rear wall to form an inclined splitting edge having a point directed downwardly in the conduit at the rear wall. The number of wedges 24 and their spacing depends upon the size and shape of the conduits and the characteristics of the coal used. They must not be spaced so close or made so large as to obstruct seriously the movement of the fuel column.

Most effective results are obtained by placing the wedges 24 on the rear wall of the conduit 15 as shown below the normal or ordinary angle of repose of the fuel indicated at A by the dot and dash line. In this location, the wedges have a splitting action on the fuel column in advance of the action of gravity and in advance of the action of the pressure fluid jets from the head 18. The wedges exert a lateral and forward force upon the upwardly moving fuel column causing the fuel column, particularly when of sticky 45 agglomerate formation, to split and crack longitudinally and consequently, breaking into a loose formation readily responsive to the action of gravity and the assisting action of the distributing jets whereby a more or less fixed angle of 50 repose of the fuel in the mouth portion is created as with ordinary operating conditions and resulting in a continuous feeding of coal.

If found desirable to supplement the splitting action of the wedges 24, pressure jets may be discharged forwardly between adjacent wedges across the fuel column as at 25. The jet openings 25 are located intermediate the upper and lower ends of the wedges or if preferred they may be disposed above the wedges as at 26 in Figure 5. These jets are intended only to assist in moving the advancing fuel into the zone of action of the distributing jets of the head 18.

Preferably, the wedges 24 and the supplemental jets 25 or 26 are formed on and in a separable section 27 of the rear wall of the conduit 15, which section 27 constitutes the lower or rearward part of the conduit cover or hood portion 23 made up of the three sections or parts 27, 28 and 29. The sections 27 and 28 are secured to the main portion of the conduit 15 by tap bolts 30 and the section 29 is in the form of a lid hinged as at 31 to the section 28 and arranged to be locked to the section 27 as by hinge bolts 32.

A cored hole 33 extending from one side to the other of the cover section 27 is threaded at one end to receive a supply line as at 34 for supplying pressure fluid to the cored hole 33 and thence to the communicating jet openings 25.

It will be seen the cover sections 27 and 28 constitute extensions of the rear and side walls of the lower portion of the conduit and that the lid section 29 is positioned intermediate the sides of the section 28. The adjacent upstanding edges 10 of the sections 27 and 28 are flanged and bolted together at 35. This hood or cover construction is rigid and durable yet comparatively inexpensive to manufacture and maintain.

By raising the lid section 29, access may be 15 had to the interior of the conduit or fuel may be delivered manually to the distributing jet. Constructing the wedges 24 and the supplemental jet 20 openings in a small separable portion of the conduit cover permits repairs or replacements to be 20 made with a minimum of time and expense.

Various other embodiments of the fuel splitting means of this invention may be constructed within the scope of the appended claims.

I claim:

1. In a stoker, in combination, an upstanding conduit having an intake opening at its lower end and a discharge mouth at its upper end, said conduit including a front wall and rear and sidewalls extending above the front wall, a distributor head positioned adjacent said discharge mouth at the upper end of the front wall, means for advancing fuel in columnar formation upwardly in said conduit rearward of said head and then forwardly over said head to points in front thereof, and fuel splitting means on the rear wall of the conduit above the level of the distributor head and rearward of but adjacent the angle of repose of the fuel column formed with the co-action of said head acting on the fuel column prior to the action of the distributor head, said splitting means including a plurality of wedge shaped members spaced transversely across said rear wall.

2. In a stoker, in combination, an upstanding conduit having an intake opening at its lower end and a discharge mouth at its upper end, said conduit including a front wall and rear and sidewalls extending above the front wall, a distributor head positioned adjacent said discharge mouth at the upper end of the front wall, means for advancing fuel in columnar formation upwardly in said conduit rearward of said head and then forwardly over said head to points in front thereof, and fuel splitting means on the rear wall of the conduit above the level of the distributor head and rearward of but adjacent the angle of repose of the fuel column formed with the co-action of said head acting on the fuel column prior to the action of the distributor head, said splitting means consisting of a plurality of wedge shaped members spaced transversely across said rear wall and a plurality of forwardly directed pressure fluid jets acting on the fuel rising between the wedge shaped members.

3. The structure as set forth in claim 1, in which each of the wedge shaped members is constructed in approximately the form of a tetrahedron disposed on the rear wall of the conduit and arranged with two triangular sides thereof extending angularly toward one another from said wall to form an inclined splitting edge having a point directed downwardly in the conduit at the aforesaid wall thereof.

4. A structure as set forth in claim 2, in which each of the wedge shaped members is constructed in approximately the form of a tetrahedron disposed on the rear wall of the conduit and arranged with two triangular sides thereof extending angularly toward one another from said wall to form an inclined splitting edge having a point directed downwardly in the conduit at the aforesaid wall thereof.
5. In a stoker, in combination, an upstanding conduit having an intake opening at its lower end and a discharge mouth at its upper end, said conduit including a front wall and rear and sidewalls extending above the front wall, a distributor head positioned adjacent said discharge mouth at the upper end of the front wall, means for advancing fuel in columnar formation upwardly in said conduit rearward of said head and then forwardly over said head to points in front thereof, and fuel splitting means on the rear wall of the conduit above the level of the distributor head and rearward of but adjacent the angle of repose of the fuel column formed with the co-action of said head acting on the fuel column prior to the action of the distributor head, said splitting means including a plurality of wedge shaped members spaced transversely across said rear wall, and that portion of said rear wall carrying the wedge shaped members being constructed as a detachable section of the wall.
6. In a stoker, in combination, an upstanding conduit having an intake opening at its lower end and a discharge mouth at its upper end, said conduit including a front wall and rear and sidewalls extending above the front wall, a distributor head positioned adjacent said discharge mouth at the upper end of the front wall, means for advancing fuel in columnar formation upwardly in said conduit rearward of said head and then forwardly over said head to points in front thereof, and fuel splitting means on the rear wall of the conduit above the level of the distributor head and rearward of but adjacent the angle of repose of the fuel column formed with the co-action of said head acting on the fuel column prior to the action of the distributor head, said splitting means consisting of a plurality of wedge shaped members spaced transversely across said rear wall, and a plurality of forwardly directed pressure fluid jets acting on the fuel rising between the wedge shaped members, and that portion of said rear wall carrying the splitting means being constructed as a detachable section of the wall.

HOWARD P. ANDERSON.
